ATTORNEY

UNITED STATES PATENT OFFICE.

MERTON B. THRIFT, OF PIEDMONT, CALIFORNIA.

FURRING STRIP.

Application filed October 11, 1922. Serial No. 593,901.

To all whom it may concern:

Be it known that I, MERTON B. THRIFT, a citizen of the United States, residing at Piedmont, in the county of Alameda and 5 State of California, have invented a new and useful Furring Strip, of which the following is a specification.

My invention relates to improvements in the furring of walls, ceilings and surfaces, 10 and in particular to an improved furring strip therefor.

Walls and other surfaces are now commonly furred with wood laths to support the plastering, or to form a foundation or 15 support for the securement thereto of wire fabric when desired, which latter forms the reinforcement for the plaster or other wall composition. In cities, the building laws require that exterior plastered walls shall be 20 reinforced.

These wooden laths are objectionable, because they are subject to swelling when the plaster is put on the wall and meshed all about them. As the wall dries out, the 25 laths also dry, but not at the same rate the plaster does, thus, these inequalities in shrinkage cause fine cracks to form in the wall that mar its appearance. This known fact causes many prospective builders of 30 homes to decide in favor of a shingle or other wood exterior, rather than any composition coating subject to cracking because of the wood laths.

Therefore, the prime object of my invention 35 is to overcome the heretofore objections to composition coatings, by the provision of a metallic furring strip not subject to swelling and shrinking, and adaptable for producing a high-grade and permanent plaster wall.

Other objects include: The ease in the manufacturing of the strips, which practically can be made from scrap material, hence very low cost; the ease of the application of them to the studding, sheathing or other base support; the continuous, smooth and comparatively long supporting surface for the wire fabric; the improved notched keying means for additional reinforcement; 45 and the provision of means for stretching and fastening the wire fabric on the wall surface.

Other objects of minor importance will appear as the description of my invention 50 progresses.

In the accompanying sheet of drawings,

I have illustrated my improved furring strip as applied to an exterior wall of a bungalow.

Figure 1 is a plan view of a strip. 60

Figure 2 is a horizontal sectional view, showing the wire lathing reinforcement and support in final position on a wall.

Figure 3 is an elevation of a portion of a wall, showing four stages of completion, 65 namely, the wood sheathing in place, the building paper and my metallic strip secured thereto, the wire lathing also secured thereto, and the finished composition coating applied. 70

A detailed description of the figures on the drawing now follow: The numeral 1 throughout the figures represents my furring strip. It is preferably made of sheet-metal and of any length desired, such for 75 example, as the width of a roll of wire fabric. In cross-section the strip is substantially V-shaped with preferably a blunt ridge, and of a depth to suit the desired thickness of the first coating of plaster. 80

Notches 2 are cut from the sides of the strip affording additional keying and holding means for the plaster. On the ridge of the strip are punched a series of small holes 3 for the reception of the lather's nails, who 85 may engage any of the holes and as many as he wishes, for the fastening of the strip to the wall.

4 represents the wood sheathing, 5 the building paper unrolled thereon and held 90 thereto by the strip 1 and nails 6. The latter are driven flush with the ridge surface to form a continuous and smooth ridge for a purpose to be described presently.

The base of the strip in cross-section, it 95 will be observed, is quite wide, this is for the purpose of affording a wide contacting support for holding the building paper in place, lest the wind get behind the paper and rip it from the sheathing, should the 100 supporting area be narrow.

On the wall the strips may be spaced and secured thereto in staggered relation. When the wall area desired to be covered is so completed, wire fabric 7 is unrolled on the strips 1 and tightly drawn by hand over a large area and secured at the ends of the unrolled portion. Then, between the staggered strips, a staple or ordinary flat-head nail 8 is driven into the sheathing until the 105 head of the nail is about flush with the fabric surface, then the head is turned over and 110

engages the wire, thus drawing and stretching it over the smooth-ridged strips in an uneven plane as seen in Figure 2.

The wall with its reinforcing foundation 5 is now ready to receive its first coating of plaster. This coating is generally of a thickness equal to the depth of the metallic furring strips, and having gauged this thickness by the said strips, the plasterer can 10 easily slide his trowel over the wire covered ridges of the strip, there being no projections whatever, as the nails 8 are driven flush or sunk below the surface and do not function in supporting the fabric. At 9 the sec- 15 ond or finishing coat is shown applied.

Having illustrated and described my in-vention in its simplest form, what I claim as new and desire Letters Patent therefor in the United States, is the following:

20 1. A sheet-metal furring strip, substan-tially V-shaped in cross-section, the ridge of said strip perforated with holes for the re-ception of fastening means, and the sides thereof notched for the keying of plaster be- 25 hind said strip.

2. A furring strip of non-swelling and non-shrinking material, having a channel-shaped cross-section throughout its entire length, the top of said strip perforated with 30 spaced holes, and the sides thereof notched between the said holes, any of the holes

adapted for the insertion of fastening means, and the unused holes together with the said notches adapted for the keying of plaster to the said strip.

3. In combination, a wall sheathing, me-tallic furring strips adapted to be fastened to said sheathing, wire lathing adapted to be supported on said strips but not secured thereto, fastening means adapted to engage said lathing between the said strips to hold the same to said sheathing in stretched ten-sion, the said metallic elements forming re-inforcement for stucco wall composition, the latter adapted to be spread on the sheathing 45 surface and between and around the meshes of said reinforcement.

4. In combination, a wall sheathing, build-ing paper, metallic furring strips adapted to be fastened to said sheathing over said paper, wire lathing adapted to be supported on said strips but not secured thereto, fas-tening means adapted to engage said lathing between the said strips to hold the same to 50 said sheathing in stretched tension, the said metallic elements forming reinforcement for stucco wall composition, the latter adapted to be spread on the sheathing surface and between and around the meshes of said rein-forcement.

In testimony whereof I affix my signature.
MERTON B. THRIFT.
